CLAIM

The ornamental design for a low profile vehicle wheel chock body, as shown and described.

DESCRIPTION

FIG. 1 is a front perspective view of a low profile vehicle wheel chock body of one embodiment of our new design.

FIG. 2 is a top view of the low profile vehicle wheel chock body of FIG. 1.

FIG. 3 is a bottom view of the low profile vehicle wheel chock body of FIG. 1.

FIG. 4 is a right side view of the low profile vehicle wheel chock body of FIG. 1.

FIG. 5 is a left side view of the low profile vehicle wheel chock body of FIG. 1.

FIG. 6 is a front end view of the low profile vehicle wheel chock body of FIG. 1.

FIG. 7 is a back end view of the low profile vehicle wheel chock body of FIG. 1.

FIG. 8 is a front perspective view of a low profile vehicle wheel chock body of another embodiment of our new design.

FIG. 9 is a top view of the low profile vehicle wheel chock body of FIG. 8.

FIG. 10 is a bottom view of the low profile vehicle wheel chock body of FIG. 8.

FIG. 11 is a right side view of the low profile vehicle wheel chock body of FIG. 8.

FIG. 12 is a left side view of the low profile vehicle wheel chock body of FIG. 8.

FIG. 13 is a front end view of the low profile vehicle wheel chock body of FIG. 8; and,

FIG. 14 is a back end view of the low profile vehicle wheel chock body of FIG. 8.

In the drawings, the broken lines do not form part of the claimed design.
